UNITED STATES PATENT OFFICE.

HARVEY D. GEYER, OF DAYTON, OHIO, ASSIGNOR TO GENERAL MOTORS RESEARCH CORPORATION, OF DAYTON, OHIO, A CORPORATION OF DELAWARE.

AUTOMOBILE THEFTPROOF DEVICE.

Application filed February 13, 1924. Serial No. 692,490.

This invention relates to a means for protecting an electric conductor against tampering therewith by unauthorized persons and is especially adapted to protect the ignition system of an automotive vehicle to prevent a thief from tapping on to the primary ignition circuit between the timer and the ignition switch.

An object of this invention is to protect an electric conductor by means which if pierced will stop or alter the normal operation of the device associated with said conductor.

Another object is to protect the portion of the primary ignition circuit of an internal combustion engine extending between the ignition timer and a lock switch located at a distance therefrom, whereby a thief cannot tap onto said circuit and thus overcome the protection afforded by the lock switch.

Another object is to protect the ignition timer by a protective covering which may be locked against removal from said timer, the same locking means also locking the timer unit from removal from the engine.

Further objects and advantages of the present invention will be apparent from the following description, reference being had to the accompanying drawings, wherein a preferred form of embodiment of the present invention is clearly shown.

In the drawings:

Fig. 1 is a plan view taken along line 1—1 of Fig. 4 showing the timer mechanism for an internal combustion engine.

Fig. 2 is an elevation, partly broken away to show interior mechanism, of the Bourdon spring unit with its cover removed and which is adapted to be secured to the top of said timer unit as shown in Fig. 4.

Fig. 3 is a top view of the part shown in Fig. 2 but shows a section through the pressure conduit connectors.

Fig. 4 is an elevation, partly broken away to show interior construction, of the assembled timer unit, Bourdon spring unit and distributor head assembled upon the engine.

Fig. 5 is a top view looking down on Fig. 4 with the distributor head removed.

Fig. 6 shows a section through the switch lock adapted to be located upon the instrument board of the vehicle.

In the drawings similar reference characters refer to similar parts throughout the several views.

In Fig. 1 numeral 10 designates the housing for the timer unit which includes the shaft 11 driven by the engine for driving the cam 12. A cam follower 13 is rigidly secured to the arm 14 pivoted at 15 and is held against the cam 12 by the bent spring 16 which presses upon arm 14 in the direction of the arrow. Spring 16 has its opposite end rigidly anchored to the stationary clip 18 which in turn is rigidly secured to the ungrounded terminal 19 of the condenser 20. As the follower 13 rides over the humps on cam 12 the movable breaker point 21 contacts and breaks contact with the stationary and grounded point 22 as will be clear from the drawings. These breaker points 21 and 22 make and break the ignition primary circuit and so cause a spark in the high tension circuit of the spark coil in the very well known manner and hence the spark coil and high tension circuits have not been completely illustrated in the drawings.

A protective housing 30 preferably made of hardened steel fits over and is fastened upon the top of the housing 10 by means of the bolts 31. Preferably the housing 30 is provided with a depending annular flange 32 which fits snugly inside of the housing 10 and so protects the parts of the timer mechanism from being tapped by a thief by drilling through the housing 10 (see Fig. 4). A Bourdon spring 35 is enclosed by and held rigidly fixed at one end within housing 30 by the connectors 36 and 37 which screw tightly together against the side wall of housing 30. The outer end of the spring 35 is provided with a forked clip 38 of suitable insulating material which is riveted to a metal clip 29 fixed to spring 35. This clip 38 moves to the dotted position 38' shown in Fig. 3 when pressure is applied to the interior of the spring 35 as will be hereinbelow described. The live side of the ignition primary circuit leads from the breaker point 21 through arm 14 and spring 16 to clip 18, thence through the upwardly projecting pin 40, which is rigidly secured to clip 18 and clears the sides of the hole 41, to the connecting lead 42 which leads to the insulated post 43 in the end of connector 36. The pin 40 is provided with a loose collar 45 which when spring 35 is in the position shown in Figs. 2 and 3 will be pressed by spring 44 against the edges of hole 41 thus making ground contact to the live side of the igni-

tion primary circuit and therefore rendering the breaker points 21 and 22 inoperative to affect said primary circuit. However when air pressure is applied to the interior of spring 35 it bends to the position shown by dotted lines 35' at which position the forked clip 38 rests under and holds the loose collar 45 in the dotted position 45' (see Fig. 2). Since the clip 38 is of non-conducting material and hence electrically insulated from spring 35 it will be clear that the ignition primary circuit will then be completely insulated from the breaker point 21 to the post 43.

15 The primary circuit leads from post 43 to the lock switch 50 ordinarily located on the instrument board of the automotive vehicle and from said switch 50 to the spark coil and battery or other current producing means, all in a manner well understood in the art. This invention provides a protective pressure conduit 51 which encloses the electrical conductor 52 throughout its passage from a point within the protective housing 30 to a point within the protective switch lock casing 50. Fig. 3 shows clearly one form of means for connecting the electrical conductor 52 to post 43 and the pressure conduit 51 with the interior of the pressure spring 35 without grounding the primary ignition circuit. The electrical circuit passes through the insulated wire 52 to the terminal 53 held in conduit 51 by the insulation plug 54. This terminal 53 bears 35 upon the end of the spring pressed sleeve 59 riding on the post 55 with which the screw binding post 43 connects. The pressure in conduit 51, which preferably is a drawn copper tube, connects with the interior of spring 35 through the passages 56, 57 and 58 as will be clear from viewing Fig. 3. The pressure conduit is provided with a union joint 60 whereby the conduit 51 and its wire 52 may be easily disconnected from the housing 30 to facilitate assembling the mechanism upon the engine and vehicle.

40 Fig. 6 shows the interior construction of the switch lock 50. The union joint 60' for connecting conduit 51 to the casting 61 may 50 be similar and preferably is identical with the union 60 shown in Fig. 3. The pressure in conduit 51 connects with the air tight chamber 62 through a passage in member 61, the wire 52 also passing therethrough and connecting with the insulated contact post 63 in partition 64. The contact post 65 is connected by a wire 66 with the insulated external binding post 67 to which the wire leading from the spark coil (not shown) is connected. The contact arm 70 is rotatable by the barrel lock 71 to make contact between posts 63 and 65 and thus establish the primary ignition circuit from the external post 67 through the wire 52 to the breaker point 21. When the lock key 72 is turned

so as to move arm 70 out of contact with posts 63 and 65 the primary circuit will be broken. The pressure conduit has all its connections at both ends sealed air tight to withstand a high pressure, preferably about 70 75 pounds per square inch. This pressure may be set up within the conduit through a valve and valve stem 75 similar to the ordinary tire valve, or by any other suitable valve.

75 The operation of this protective device is as follows: When the ignition switch 70 is turned off and the key 72 withdrawn a thief may attempt to tap onto conductor 52 leading from the timer housing in order to connect up the primary circuit through the breaker points 21 and 22. But since conductor 52 is entirely enclosed by high pressure in conduit 51 any such attempt will necessarily release this pressure, which release will cause the Bourdon spring 35 to move to the position shown in full lines in Figs. 2 and 3, thus permitting spring 44 to move loose collar 45 into electrical contact with the housing 30 and thus ground the contact point 21 rendering the breaker points entirely inoperative. If the thief should again apply pressure to the closed conduit 51 the fork 38 on spring 35 in again moving to the dotted position of Fig. 3 will pass above collar 45 and hence can have no effect in raising collar 45 from its grounded position. The collar 45 rests within a counter-sunk recess 34 to prevent the thief from raising it by any means which may be inserted through a small hole in the housing 30. It will be clear that the pressure system protects the primary circuit from a point well within the protective housing 30, namely post 43, to a point well within the protective housing 50, namely post 63. Both of these protective casings are preferably hardened to resist drilling.

100 The protective casing 30 is provided with a removable cover 80 which fits snugly within the top of housing 30 and is locked thereon by the key lock 81 which is provided with a rotatable member 82 movable within slot 83 in bolt 81. The cover 80 is also provided with the projecting portion 85 which extends over the head 86 of the hold down bolt 87 screwed into a part 93 integral with the engine which bolt prevents the upward withdrawal of the entire timer unit from the engine. It is thus clear that when lock 81 is locked the bolts 81 cannot be removed nor can the bolt 87 be removed, hence all the parts are locked in position. The projection 85 is provided with an elongated slot 88 and the arm 90 is provided with a similar elongated slot 89 to permit the timer unit to be rotated about its axis by lever 91 for advancing and retarding the timer in the usual manner. A spring pressed sliding collar 92 on bolt 87 presses upon the arm 90 and thus 105 110 115 120 125 130

provides sufficient friction to hold the timer unit in any position to which it is rotated by arm 91.

The bolt 87 is preferably covered with a hardened easily rotatable sleeve 95 to protect bolt 87 from being sawed or cut into by a thief. If the thief attempts to break bolt 87 off at its base the weakened sections 96 and 97 in the sleeve 95 and bolt 87 will cause these parts to break at these points. The spherical head 98 will then be impossible to hold with any tool for unscrewing the base of bolt 87. Preferably the cover 80 is held down on the housing 30 on both sides of the projection 85 by two lugs 100 which enter the slots 101 in the cover 80 as clearly shown in Figs. 4 and 5.

The distributor head 105 fits above housing 30 and is clamped thereon by the spring 29 clamps 106 in the ordinary manner. The revolving distributor arm 107 is driven by shaft 11 through the short shaft extension 108 extending through the housing 30 and having suitable bearing therein.

The embodiment of the invention illustrated and described herein is such as can be made as an accessory and applied to the present form of timer and distributor units, the particular one shown being that for a Buick automobile. However, a timer and distributor unit may be specially designed to embody this invention and thus reduce the size and number of parts required. For instance, the housings 10 and 30 may be integral, or the timer housing 10 may be slightly enlarged and the Bourdon spring 35 and its cooperating parts housed therein thus greatly reducing the size of the entire unit.

While the form of embodiment of the present invention as herein disclosed, constitutes a preferred form, it is to be understood that other forms might be adopted, all coming within the scope of the claims which follow.

45 What is claimed is as follows:

1. In combination with an internal combustion engine having an ignition primary circuit and a timer for making and breaking said ignition primary circuit, an electric switch for said ignition circuit located at a distance from said timer, a conduit enclosing the circuit conductor between said switch and timer and having fluid under a pressure different from atmospheric therein, and means associated with said timer and operable by a change of pressure in said conduit to render the ignition system inoperative.

2. In combination with an internal combustion engine having an ignition system and a timer therefor, an ignition circuit leading from said timer and having a switch located at a distance from said timer, a conduit enclosing the circuit conductor between the timer and switch and confining fluid

under a different degree of pressure from the surrounding atmosphere, and means operable by a change of pressure in said conduit to render the ignition system inoperative.

3. In combination with an internal combustion engine having an ignition system and a timer therefor located in an inaccessible position, an ignition circuit leading from said timer through an accessible location and having a switch therefor located in an inaccessible position, a conduit enclosing the circuit conductor throughout its passage through the accessible location and confining fluid under a pressure different from atmospheric, and means operable by a change of pressure in said conduit to render the ignition system inoperative.

4. In combination with an internal combustion engine having an ignition system and a timer therefor, an ignition circuit leading from said timer and having a switch located at a distance from said timer, a conduit enclosing the circuit conductor between the timer and switch and confining fluid under a different degree of pressure from the surrounding atmosphere, and means associated with said timer and operable by a change of pressure in said conduit to render the ignition system inoperative.

5. In combination with an internal combustion engine having an ignition system and a timer therefor, located in an inaccessible position, an ignition circuit leading from said timer through an accessible location and having a switch therefor located in an inaccessible position, a conduit enclosing the circuit conductor throughout its passage through the accessible location and confining fluid under a pressure different from atmospheric, and means associated with said timer and operable by a change of pressure in said conduit to render the ignition system inoperative.

6. In combination with an internal combustion engine having an ignition system and a timer therefor located in an inaccessible position, an ignition circuit leading from said timer through an accessible location and having a switch therefor located in an inaccessible position, a conduit enclosing the circuit conductor throughout its passage through the accessible location and confining fluid under a pressure different from atmospheric, and means located in an inaccessible position and operable by a change of pressure in said conduit to render the ignition system inoperative.

7. In combination with an internal combustion engine having an ignition system and a timer therefor located in an inaccessible position, an ignition circuit leading from said timer through an accessible location and having a switch therefor located in an inaccessible position, a conduit enclosing

- the circuit conductor throughout its passage through the accessible location and confining fluid under a pressure different from atmospheric, and means operable by a change of 5 pressure in said conduit to render said engine inoperative.
8. In combination with an internal combustion engine having an ignition system and a timer therefor driven by said engine, a 10 protective casing around said timer, an ignition circuit leading from said timer and having a switch therein located at a distance from said casing, a protective casing about said switch, a conduit enclosing the circuit 15 conductor between said protective casings and confining fluid under a pressure different from atmospheric, and means operable by a change of pressure in said conduit to render the ignition system inoperative.
9. In combination with an internal combustion engine having an ignition system and a timer therefor driven by said engine, a protective casing around said timer, an ignition circuit leading from said timer and 20 having a switch therein located at a distance from said casing, a protective casing about said switch, a conduit enclosing the circuit conductor between said protective casings and confining fluid under a pressure different from atmospheric, and means associated 25 with said timer and operable by a change of pressure in said conduit to render said engine inoperative.
10. In combination with an internal combustion engine having an ignition system and a timer therefor driven by said engine, a protective casing around said timer, an ignition circuit leading from said timer and having a switch therein located at a distance 30 from said casing, a protective casing about said switch, a conduit enclosing the circuit conductor between said protective casings and confining fluid under a pressure different from atmospheric, and means associated 35 with said timer and operable by a change of pressure in said conduit to render the ignition system inoperative.
11. In combination with an internal combustion engine having an ignition system and a timer therefor driven by said engine, a protective casing around said timer, an ignition circuit leading from said timer and having a switch therein located at a distance 40 from said casing, a protective casing about said switch, a conduit enclosing the circuit conductor between said protective casings and confining fluid under a pressure different from atmospheric, and means located in 45 an inaccessible position and operable by a change of pressure in said conduit to render the ignition system inoperative.
12. In combination with an internal combustion engine having an ignition system and a timer therefor driven by said engine, a protective casing around said timer, an ignition circuit leading from said timer and having a switch therein located at a distance 50 from said casing, a protective casing about said switch, a conduit enclosing the circuit conductor between said protective casings and confining fluid under a pressure different from atmospheric, and means located in 55 said timer protective casing and operable by a change of pressure in said conduit to render the ignition system inoperative.
13. In combination with an internal combustion engine having an ignition system and a timer therefor driven by said engine, a protective casing around said timer, an ignition circuit leading from said timer and having a switch therein located at a distance 60 from said casing, a protective casing about said switch, a conduit enclosing the circuit conductor between said protective casings and confining fluid under a pressure different from atmospheric, and means operable by a change of pressure in said conduit to render said engine inoperative. 70
14. In combination with an internal combustion engine having an ignition system and a timer therefor driven by said engine, a protective casing around said timer, an ignition circuit leading from said timer and having a switch therein located at a distance 75 from said casing, a protective casing about said switch, a conduit enclosing the circuit conductor between said protective casings and confining fluid under a pressure different from atmospheric, and means associated 80 with said timer and operable by a change of pressure in said conduit to render said engine inoperative. 85
15. In combination with an internal combustion engine having an ignition system and a timer therefor driven by said engine, a protective casing around said timer, an ignition circuit leading from said timer and having a switch therein located at a distance 90 from said casing, a protective casing about said switch, a conduit enclosing the circuit conductor between said protective casings and confining fluid under a pressure different from atmospheric, and means located in 95 an inaccessible position and operable by a change of pressure in said conduit to render said engine inoperative. 100
16. In combination with an internal combustion engine having an ignition system and a timer therefor driven by said engine, a protective casing around said timer, an ignition circuit leading from said timer and having a switch therein, a lock for said switch, a protective casing about said switch, a closed conduit enclosing the circuit conductor between said protective casings and 110 confining fluid under a pressure different from atmospheric, and means operable by a change of pressure in said conduit to render the ignition system inoperative. 115
17. In combination with an internal com- 120

- bustion engine having an ignition system and a timer therefor driven by said engine, a protective casing around said timer, an ignition circuit leading from said timer and having a switch therein, a lock for said switch, a protective casing about said switch, a closed conduit enclosing the circuit conductor between said protective casings and confining fluid under a pressure different from atmospheric, and means protected by said timer casing and operable by a change of pressure in said conduit to render the ignition system inoperative.
18. In combination with an internal combustion engine having an ignition system and a part driven by the engine for producing the ignition spark, a protective casing around said part, an ignition circuit leading from within said casing and having a switch for said circuit located at a distance from said casing, a protective casing about said switch, a conduit enclosing the circuit conductor throughout its length between said protective casings and confining fluid under a pressure different from atmospheric, and means operable by a change of pressure in said conduit to render said ignition system inoperative.
19. In combination with an internal combustion engine having an ignition system and a part driven by the engine for producing the ignition spark, a protective casing around said part, an ignition circuit leading from within said casing and having a switch for said circuit located at a distance from said casing, a protective casing about said switch, a conduit enclosing the circuit conductor throughout its length between said protective casings and confining fluid under a pressure different from atmospheric, and means located in said first protective casing and operable by a change of pressure in said conduit to render said ignition system inoperative.
20. In combination with an internal combustion engine having an ignition system and a part driven by the engine for producing the ignition spark, a protective casing around said part, an ignition circuit leading from within said casing and having a switch for said circuit located at a distance from
- said casing, a protective casing about said switch, a conduit enclosing the circuit conductor throughout its length between said protective casings and confining fluid under a pressure different from atmospheric, and means associated with said driven part and operable by a change of pressure in said conduit to render said ignition system inoperative.
21. In combination with an internal combustion engine having an ignition system and a part driven by the engine for producing the ignition spark, a protective casing around said part, an ignition circuit leading from within said casing and having a switch for said circuit located at a distance from said casing, a protective casing about said switch, a conduit enclosing the circuit conductor throughout its length between said protective casings and confining fluid under a pressure different from atmospheric, and means operable by a change of pressure in said conduit to render said engine inoperative.
22. In combination with an internal combustion engine having an ignition system and a part driven by the engine for producing the ignition spark, a protective casing around said part, an ignition circuit leading from within said casing and having a switch for said circuit located at a distance from said casing, a protective casing about said switch, a conduit enclosing the circuit conductor throughout its length between said protective casings and confining fluid under a pressure different from atmospheric, and means associated with said driven part and operable by a change of pressure in said conduit to render said engine inoperative.
23. In combination with an internal combustion engine, an electric circuit, means associated with said circuit for rendering said engine operative or inoperative at the will of the operator, a protective conduit enclosing a portion of the circuit conductor and confining a fluid under a pressure different from atmospheric, and means operable by a change of pressure in said conduit to render said engine inoperative.

In testimony whereof I hereto affix my signature.

HARVEY D. GEYER.
